UNITED STATES PATENT OFFICE.

WILLIAM L. DOAK, OF PITTSBURGH, PENNSYLVANIA.

FIELDER'S GLOVE.

1,426,824.

Specification of Letters Patent. Patented Aug. 22, 1922.

Application filed April 18, 1921. Serial No. 462,316.

To all whom it may concern:

Be it known that I, WILLIAM L. DOAK, a citizen of the United States, residing at Pittsburgh, Pennsylvania, have invented a 5 certain new and useful Improvement in Fielders' Gloves, of which the following is a full, clear, and exact description, such as will enable others skilled in the art to which it appertains to make and use the same.

10 This invention relates to baseball gloves.

The main object of the invention is to provide a fielder's glove in which the thumb and index finger of the glove are connected together by a plurality of strands that extend 15 transversely across the space between the thumb and index finger and co-operate with said parts to form a pocket which will conform or adjust itself automatically to a ball caught by the glove.

20 Another object is to provide a fielder's glove of the character above referred to in which the strands that connect the thumb and index finger of the glove together are combined with the glove in such a way as to 25 not interfere with the flexibility of the thumb and index finger or tear said parts when said strands are subjected to strain from a ball caught by the glove.

And still another object is to provide a 30 fielder's glove that comprises a thumb and index finger, an adjustable lacing for connecting said parts together and a stay for reinforcing the seam between the thumb and index finger.

35 Figure 1 of the drawings is a perspective view of a fielder's glove constructed in accordance with my invention.

Figure 2 is a similar view, showing how the lacing extending between the thumb and 40 index finger functions when a ball is caught by the glove; and

Figure 3 is a sectional view, taken on the line 3—3 of Figure 1.

Referring to the drawings which illustrate the preferred form of my invention, A 45 designates a fielder's glove provided with a thumb 1, an index finger 2 and a plurality of strands α and γ connected to said thumb and index finger and extending transversely 50 across the space between same, as shown in Figure 1. When the glove is used for catching a ball, as shown in Figure 2, the strands α and γ co-operate with the thumb and index finger to form a pocket that conforms to 55 or which automatically adjusts itself to the curvature of the ball, due to the fact that

the strands α and γ are spaced apart and the strand γ is arranged high enough above the crotch of the space between the thumb and index finger of the glove to permit the ball 60 to rest or seat itself in said crotch. In other words, the strands α and γ virtually form a skeleton-like pocket for a ball positioned between the thumb 1 and index finger 2 of the glove, thereby permitting the ball to assume 65 such a position after it has come in contact with the thumb and index finger of the glove that it will be retained or held securely by the pressure exerted on same by the thumb and index finger of the hand of 70 the fielder wearing the glove.

In order that the pocket formed by the strands α and γ may be varied to change the dimensions or the shape of said pocket, I prefer to use a lacing of leather or other 75 suitable material to form the strands α and γ and thread said lacing through holes in the thumb and index finger of the glove in such a way that the length of both strands can be increased or diminished when it is 80 desired to increase or diminish the width of the space between said thumb and index finger, or the length of one strand can be increased by pulling on the other strand. In the form of my invention herein shown the 85 strands α and γ are securely connected at one end to the thumb 1 of the glove and the other ends of said strands are passed freely through holes in the index finger 2 of the glove and joined together by a portion z of 90 the lacing which forms said strands. Accordingly, if one strand is subjected to a greater strain or pull than the other strand, the strand which is subjected to the greatest strain will lengthen and the other strand 95 will shorten automatically. This is a very desirable feature of my glove, in that it insures the strands α and γ adjusting themselves automatically to the curvature of the ball caught by the glove, the force which 100 the ball exerts on the bottom strand γ tending to shorten the top strand α , due to the fact that said top strand engages the ball at a higher point on the surface of the ball.

Another advantage that results from connecting the strands to the glove in the manner above described is that the strand first engaged by the ball will give or yield slightly, and thus take up the shock of the ball in such a way as to reduce the liability 110 of the strands tearing the glove.

The strands α and γ are detachably con-

nected to the thumb 1 of the glove so as to permit the length of both strands to be increased or decreased when it is desired to vary the width of the space between the 5 thumb and index finger of the glove, and while it is immaterial how the free ends of the strands α and γ are connected to the thumb 1 of the glove, I prefer to pass said strands forwardly through holes in the 10 thumb 1 so that portions of said strands extend over the front side of said thumb and then pass said strands rearwardly through holes in the thumb and form knots α' and γ' , respectively, in said strands, as shown in 15 Figure 2, so as to prevent them from pulling out of the holes in the thumb. By arranging the lacing constituting the strands α and γ of the glove in this manner said strands will be positioned at the rear of the 20 thumb and index finger of the glove and will naturally assume the form of two curved loops connected together at one end by a portion β arranged on the front side of the index finger 2 and having their free ends 25 laced through the thumb 1 and secured by knots arranged on the rear side of said thumb.

In order that the lacing will not interfere with the flexibility of the thumb and index 30 finger of the glove or tear the material from which said thumb and index finger are formed, I prefer to arrange aligned eyelets w in the front and rear sides of the thumb 1 and index finger 2 at the points where the 35 lacing passes through said parts and make the outer covering of said thumb and index finger full enough so that the lacing can pass between same and the inner lining u of the glove, as shown in Figure 3. As the 40 lacing is located outside of the inner lining of the thumb and index finger of the glove it will not rub against the thumb and index finger of the user's hand, and as the lacing is threaded through holes in the outer covering of the thumb and index finger of the 45 glove, instead of through webs, flanges or similar elements stitched to said parts, the glove is as flexible as a fielder's glove in which the thumb and index finger are not connected or joined together. Furthermore, 50 as the outer cover of the glove is provided with two aligned eyelets at each point where the lacing passes through same, there is little liability of the lacing tearing the outer cover of the glove. I also prefer to arrange 55 a stay 3 of leather or other suitable material at the crotch of the space between the thumb and index finger of the glove, as shown in Figure 1, so as to prevent the seam of the 60 crotch from ripping, but it will, of course, be understood that this stay is not essential and can be omitted without departing from my invention.

I am aware of the fact that fielders' gloves 65 have heretofore been devised in which the

thumb and index finger of the glove are connected together by a gusset or web stitched to said parts, but such a glove is objectionable in that it has no provision for varying the width of the space between the thumb 70 and index finger, and moreover, it prevents a ball caught by the glove from seating itself in the crotch of the space between the thumb and index finger in such a way that it can be held securely by the thumb and index 75 finger of the hand of the wearer. In my improved glove the space between the thumb and index finger can be varied easily by simply changing the adjustment of the lacing that connects said parts together, and as the 80 means which connects the thumb and index finger together consists of a plurality of spaced strands that virtually form a pocket of skeleton construction, said pocket will conform or adjust itself automatically to 85 the curvature of a ball positioned between the thumb and index finger of the glove and seated in the crotch of the space between said parts.

Having thus described my invention, what 90 I claim as new and desire to secure by Letters Patent, is:

1. A fielder's glove, comprising a thumb and index finger that can move freely towards and away from each other so as to 95 form a ball pocket of variable size, and a plurality of strands leading from the rear side of said thumb and index finger so as to form a rear wall for said ball pocket that will adjust itself automatically to a ball positioned 100 between said thumb and index finger, said strands being joined at one end by a portion that passes freely through the index finger, and knots at the opposite ends of said strands that serve to secure said strands 105 to the thumb of the glove.

2. A fielder's glove, provided with a thumb and an index finger, each of which comprises an outer cover and inner lining, and a lacing for connecting said parts together 110 threaded through holes in a double portion or in two thicknesses of the outer cover of each of said parts and leading from the rear sides of said thumb and index finger so as to form the rear side of a ball pocket whose 115 sides are formed by said thumb and index finger.

3. A fielder's glove, provided with a thumb and an index finger, each of which comprises an outer cover and an inner lining, 120 a plurality of pairs of aligned eyelets in the front and rear sides of the outer cover of each of said parts, and an adjustable lacing threaded through said eyelets and extending transversely across the space between said 125 thumb and index finger so as to form the rear side of a ball pocket whose side portions are formed by said thumb and index finger.

4. A fielder's glove, comprising a thumb, 130 an index finger, and a lacing for joining said

parts together, said lacing being so arranged that portions of same extend longitudinally of said thumb and index finger on the front sides of same and portions of said lacing 5 lead from the rear side of said parts transversely of the space between same so as to form the rear wall of a skeleton-like ball pocket whose side walls are formed by said thumb and index finger.

10 5. A fielder's glove, comprising a thumb

and index finger combined in such a way that they can separate sufficiently to permit a caught ball to pass between same, and a plurality of transversely-disposed strands connected with said thumb and index finger 15 and being of sufficient length to form a yielding back stop for a caught ball, which, when engaged by the ball, tends to draw said thumb and index finger around the ball.

WILLIAM L. DOAK.
